UNITED STATES PATENT OFFICE.

RICHARD J. NORTON, OF WASHINGTON, DISTRICT OF COLUMBIA.

ADJUSTER FOR FLEXIBLE PENDANTS.

1,108,468.

Specification of Letters Patent. Patented Aug. 25, 1914.

Application filed October 25, 1912. Serial No. 727,745.

To all whom it may concern:

Be it known that I, RICHARD J. NORTON, a citizen of the United States, residing at Washington, District of Columbia, have invented certain new and useful Improvements in Adjusters for Flexible Pendants, of which the following is a specification, reference being had to the accompanying drawing.

10 This invention relates to fixture supports and more particularly to a means for adjustably positioning a flexible pendant fixture in a vertical plane.

One of the many objects of this invention 15 is to provide a device of the nature described which may be readily installed on a pendant fixture without detaching any of the parts of the latter.

Another object is to have the device so arranged that no severe or relatively injurious 20 stresses will be put upon parts of the pendant or its insulation.

A further object is to arrange the means for balancing the fixture proper so that its 25 weight may be readily adjusted and after the same is in position.

Other objects are, to arrange the parts of the device so that they may be quickly detached or fastened together without the use 30 of tools; to eliminate extra cords for supporting the balancing weight; to arrange the support for the weight whereby the latter will be kept out of contact with the pendant proper, and to have the device as simple and compact as possible and consistent 35 with the work to be done; other objects of this invention will be apparent as it is more fully set forth.

In most devices for adjustably supporting 40 pendants a separate support has to be provided for the adjuster whether a spring or weight is used, and in some cases several are used, and require a large amount of flexible cord or tubing in order to make their use 45 with the device convenient. This invention avoids these disadvantages in that it is directly attached to the flexible pendant cord or tubing and requires or uses up about two inches of the latter. At the same 50 time no excessive stresses are placed on the cord or tubing at any time, and the device can be installed or removed in a relatively very short time.

55 In the accompanying drawings which show a modification of this invention, Fig. 1 shows an embodiment of this invention

applied to a flexible cord pendant fixture. Fig. 2 is a detail of the adjuster parts. Fig. 3 is a sectional detail through the weight. Fig. 4 is a detail showing a desired form of 60 groove in the clamping member. Fig. 5 is a detail of the adjuster in its most compact position.

Similar reference characters refer to similar parts throughout the drawings.

The reference character 1, represents the flexible cord of an electric pendant fixture, 2 being the canopy or rosette and 2' the socket and lamp shade for the same. At a suitable point 4 of the cord, a clamp 3 is attached, 70 the latter being preferably of the form shown in the drawings.

5 and 6 are respectively the legs of the clamp and are provided with V-shaped grooves 7 therein, for the cord to lie and be 75 clamped on. The leg 6 is hingedly connected to clamp proper and is locked in its closed position by means of a threaded bolt 8, which extends through the leg 6 and threads into the leg 5; a suitable head 9 being provided on it, so that it can be actuated by hand. A pair of legs 10 and 11, extending away from the clamp proper in an opposite direction to those already mentioned serve as holders for a journal shaft 12 for a pulley 80 13 which freely rotates thereon. The end 14 of the shaft 12 threads into the leg 10 and its head 15 is preferably made as shown.

The balancing member of the device consists of a quasi-spherical body 16 of relatively heavy material, provided with a deep curved groove 17 adapted to permit a pulley 18 to be disposed therein. A removable pin 19 disposed in holes 20 in the body 16 serves to help the pulley in place. The principle of this pin is similar to that of the parts 12 and 8. At the lowest portion of the groove 17 a hole leads to a space or hollow 21 provided in the body. This hollow is for the reception of shot or other 100 loading medium, so that the weight of the fixture can be accurately counterbalanced.

It will be noted that the groove 17 is sufficiently deep to permit the shot to be easily placed in the weight even when it 105 is positioned with the cord in place. In order to permit the cord to be extended as far as possible the body is cut away at one side 22 of the groove 17, in such a way as to permit the pulleys to come into close 110 contact if desired. This last position of the pulleys gives them a slight braking ac-

tion which permits the lamp to be handled and raised a slight amount for general purposes, without permitting the body to descend.

5 It is unnecessary to detail the position of the lamp cord in the device as the drawings indicate the same and it can be readily appreciated from the foregoing description that the pulleys can be quickly removed 10 and replaced and the clamp fastened on at 4, without any tools or removal of or interference with any parts of the fixture itself.

15 While but one form of the device is shown it is understood that this application for patent is not limited to that particular form or in any other way otherwise than limited by the prior art, as many modifications in the same may be made without departing from the principles thereof and coming 20 within the scope of the appended claims.

Having thus described my invention what I claim is:

1. In combination with a flexible cord and 25 pendant fixture, an adjuster comprising a body having two bifurcated end portions, one of which portions is adapted to clamp and offset the flexible cord between it and be readily slidable thereon and the other end portion is adapted to receive, and provided with, a pulley, means for retaining the pulley in place in the portion, said pulley being grooved for the cord, and a 30 balancing member having a pulley recessed

therein and means for retaining the pulley in place adapted to be quickly removed and 35 replaced, said pulley being grooved to ride on said cord, said balancing member being arranged to counterbalance the lamp and take up the cord when adjusted.

2. In combination with a flexible cord and 40 pendant fixture, an adjuster comprising an elongated body having its end portions bifurcated, one portion being adapted to clamp and offset the flexible cord and to be 45 slidable thereon, and to cause the body to extend angularly out from said cord, the other of said portions being adapted to retain a pulley, said pulley being grooved for the flexible cord and disposed away from the cord offset by the first portion, and a 50 balancing member having a pulley completely recessed therein and arranged to ride on said cord and bring it adjacent to the inside of the member whereby it will not be able to jump the cord, and means 55 for retaining the wheel easily removably in place, said balancing member being arranged to counterbalance the fixture and take-up the cord when adjusted and avoid contact with the cord adjacent to the lamp.

60 In testimony whereof I hereunto affix my signature in the presence of two witnesses.

RICHARD J. NORTON.
